UNITED STATES PATENT OFFICE.

LOUIS W. NIMSCHKE, OF NEW YORK, N. Y.

LOCK-HINGE.

SPECIFICATION forming part of Letters Patent No. 394,788, dated December 18, 1888.

Application filed August 1, 1888. Serial No. 281,626. (No model.)

To all whom it may concern:

Be it known that I, LOUIS W. NIMSCHKE, of the city, county, and State of New York, have invented certain new and useful Improvements in Lock-Hinges, of which the following is a specification.

This invention relates to an improved lock-hinge for shutters, whereby the shutter is locked in a firm and reliable manner when open and is readily and conveniently released when closing the same; and the invention consists of a shutter-hinge provided with a downward-extended pintle and a spring-locking latch that is guided by a slot in it, through which slot said pintle passes and adapted to engage the shank of the shutter-hinge, said latch being made integral with the strap attached to the window-frame.

In the accompanying drawings, Figure 1 represents a front elevation of a window, showing one shutter in open and one in closed position, said shutter being provided with my improved lock-hinge. Fig. 2 is a side elevation of a lock-hinge, drawn on a larger scale. Figs. 3 and 4 are end elevations showing the shutter respectively in open and closed position, and Fig. 5 is a top view of the lock-hinge.

Similar letters of reference indicate corresponding parts.

Referring to the drawings, A represents a shutter-hinge, of which one sleeve, *a*, is applied by an angle-iron made integral with the shank of the sleeve to the shutter-stile, while the second sleeve, *b*, is applied to the window-casing. The pintle *B* of the lock-hinge is extended below the sleeve *b* and passed through a slot, *d*, of a spring-latch, *D*, which latter is bent up at the outer end into the path of the shank *a'* of the upper hinge-sleeve, *a*.

The spring-latch *D* is made integral with a U-shaped spring, *D'*, the shank of which is secured to the window-casing and forms the fastening-strap. This spring and latch is bent from one piece of metal and furnishes a

sufficient spring action to securely lock the shutter in open position. When the shutter is being opened, the shank *a'* of the upper sleeve, *a*, passes over the bent upper end of the spring-latch *D* and depresses the same until it has passed over the edge of the spring-latch and is locked by the same, as shown on the left-hand side of Fig. 1 and in Fig. 3. For closing the shutter the bent end of the spring-latch is forced down, so as to be clear of the shank *a'* of the sleeve *a*. The slot *d* in the spring-latch serves to limit, in connection with the pintle *B*, the extent of motion of the spring-latch and prevents thereby the over-straining and bending out of shape of the spring action in the latch. As the spring-latch can be made at comparatively small expense, and as this is the only additional piece required for locking the shutter, the locking-hinge can be furnished at a comparatively small expense, while forming a strong and durable locking device for the shutter-hinge.

Having thus described my invention, I claim as new and desire to secure by Letters Patent—

1. The combination, with a fixed pintle-sleeve, a movable pintle-sleeve applied to the shutter, a pintle extended below the fixed pintle-sleeve, and a spring-latch made integral with the fastening-strap and provided with a slot passing around the pintle, substantially as set forth.

2. In a lock-hinge for shutters, a spring-latch composed of a fastening-strap having a U-shaped spring portion and a curved end provided with a slot for passing over the pintle of the hinge, substantially as set forth.

In testimony that I claim the foregoing as my invention I have signed my name in presence of two subscribing witnesses.

LOUIS W. NIMSCHKE.
